CLAIM

The ornamental design for a decorative element for a vehicle, as shown and described.

DESCRIPTION

This application contains subject matter related to the following co-pending U.S. patent application:

Application Ser. No. 29/311,753, filed on even date herewith and entitled “Decorative Element for a Vehicle”.

FIG. 1 is a left perspective view of a first embodiment of a decorative element for a vehicle according to my design;

FIG. 2 is a right perspective view thereof;

FIG. 3 is a front view thereof;

FIG. 4 is a top view thereof;

FIG. 5 is a bottom view thereof;

FIG. 6 is a left side view thereof; and

FIG. 7 is a right side view thereof.

FIG. 8 is a right perspective view of a second embodiment of the decorative element for a vehicle according to my design;

FIG. 9 is a left perspective view thereof;

FIG. 10 is a front view thereof;

FIG. 11 is a top view thereof;

FIG. 12 is a bottom view thereof;

FIG. 13 is a left side view thereof; and,

FIG. 14 is a right side view thereof.

In the drawings, the broken lines show portions of a decorative element for a vehicle and form no part of the claimed design.
